UNITED STATES PATENT OFFICE

2,571,367

TOILET FLUSH VALVE

Julius S. Judell, Shorewood, Wis., assignor to
 Milwaukee Flush Valve Co., Milwaukee, Wis.,
 a corporation of Wisconsin

Application June 23, 1948, Serial No. 34,633

4 Claims. (Cl. 137—104)

1

My present invention relates generally to improvements in the manufacture of toilet plumbing, and relates more specifically to various improvements in the construction and operation of flush valve assemblies for toilets or the like.

The primary object of the present invention is to provide an improved toilet flush valve assembly which is simple in construction, flexible in its adaptations, and highly efficient in operation.

Various types of so-called "ball cocks" or flush valves for toilets have heretofore been proposed and used commercially with varying degrees of success, but most of these prior devices are objectionable either because they are excessively noisy in operation, or because they are too complicated and difficult to repair, or because they cannot be conveniently and positively regulated and adjusted to produce proper and rapid flow of flushing liquids, or because they quickly become leaky and messy, or because parts thereof are too frail to withstand normal installation and use for prolonged periods of time, or because they do not comply with plumbing codes and the like. The prior ball cocks have therefore been a constant source of annoyance to plumbers and users for one or more of the above mentioned reasons as well as for others, especially when installed in homes and other places where the requirements for silence and safety are imperative and the services of expert mechanics are not always available.

It is therefore an important object of my present invention to provide an improved ball cock assembly for toilets, which obviates all of the above specified objectionable features, and which may be readily installed and maintained in effective operation with minimum attention.

Another important object of this invention is to provide a flush valve assembly which is indeed exceedingly quiet in operation, and which embodies only a few simple but durable parts adapted to be conveniently adjusted so as to insure silent functioning in spite of variable conditions of supply liquid pressure.

A further important object of the invention is to provide a simplified ball cock unit capable of being installed in various types and styles of flush tanks without difficulty, and which may be readily regulated to vary the quantity and rate of flow of the liquid supply by means of simple and easily manipulable adjusting mechanism.

Still another important object of the present invention is to provide an improved control valve assembly for toilet flush tanks, wherein the liquid supply may be shut off within the assemblage

2

and in which annoying leakage and dripping of liquid is effectively eliminated, with the aid of simple and long lasting valves.

An additional important object of my invention is to provide a toilet flush valve unit which is sturdily constructed to resist breakage of parts, and which complies with all known plumbing codes and requirements, especially as to silence, safety and back siphoning of liquid.

10 Another important object of my present invention is to provide a greatly improved ball cock assembly adapted to be manufactured and sold at moderate cost, and which may be installed and maintained in efficient operating condition by a novice and with the aid of ordinary tools.

These and other objects and advantages of the invention will be apparent from the following detailed description.

A clear conception of the several features constituting the present improvement, and of the construction and operation of a typical ball cock embodying the same, may be had by referring to the drawings accompanying and forming a part of this specification wherein like reference characters designate the same or similar parts in the various views.

Fig. 1 is a side view of one of the improved float actuated ball cock units showing the same associated with fragments of the liquid supply and overflow pipes, and in the act of delivering full streams of liquid to the flush tank and overflow;

Fig. 2 is another side view of the same unit, showing the parts in position just prior to final interruption of the supply liquid flow;

Fig. 3 is a rear and end perspective view of one of the improved flush valve units installed within a flush tank and also showing the tank discharge valve associated with the tank bottom;

Fig. 4 is an enlarged longitudinal section through the liquid supply valve casing of the ball cock unit, showing both valves partially open; and

Fig. 5 is a likewise enlarged partial transverse section through the valve casing and associated parts, the section having been taken along the line 5—5 of Fig. 4.

While the features of the present improvement have been shown herein as applied to a float actuated unit supported by an upright pressure liquid supply pipe located within a flush tank, it is not my desire to unnecessarily limit the scope or utility of these improved features by virtue of this restricted embodiment; and it is also contemplated that specific descriptive terms used

herein be given the broadest possible interpretation consistent with the disclosure.

Referring to the drawings, the typical improved ball cock assemblage shown, comprises in general, a unitary main body or valve casing 1 having a lower supply liquid inlet opening 8 and an upper liquid outlet opening 9 disposed on opposite sides of a partition 10 which divides the casing into chambers 11, 12 and is provided with a central port and valve seat 13; a manually adjustable supply liquid shut-off valve 15 associated with the casing 1 in alignment with the inlet opening 8 and extending through the chamber 11; a spout fitting or connection 16 swingably adjustably associated at one end with the casing 1 at the outlet opening 9, and having at its opposite end a downwardly directed discharge nozzle 17 provided with a set of flow silencing or hushing screens 18 while its medial portion is provided with an overflow pipe refill tube 19; an automatically operable plunger valve 20 slidable within a horizontal bore 21 formed in the casing 1 in alignment with the central partition opening, and having a valve disk 22 embedded in its inner end and cooperating with the seat 13 while its outer end is provided with a flat head 24; a valve actuating lever 25 having one end swingably suspended from the casing 1 by a pivot 26 and provided with an adjusting screw 27 which is cooperable with the valve head 24, while its opposite swinging end has a buoyant float 28 secured thereto; and means carried by the medial portion of the lever 25 and coacting with the valve casing, for retarding the valve closing motion of the float 28 and lever 25 so as to augment the buoyancy of the float at a predetermined moment in order to insure quick and positive closing of the valve 20.

The unitary main casing 1 may be formed of any durable corrosion resistant metal, and the supply inlet opening 8 is internally threaded for screw thread attachment to the upper extremity of an upright fresh liquid supply pipe 30, while the outlet opening 9 is likewise internally threaded for screw thread attachment of the spout 16 thereto. These screw thread attachments will obviously permit the casing 1 and the various elements associated therewith to be swung for adjustment purposes in a horizontal plane about the central axis, of the fixed liquid supply pipe 30, and will also permit the spout 16 to be likewise adjusted relative to the casing 1 about the central axis of the opening 9 so as to vary the positions of the liquid jets 31, 32 normally emanating from the nozzle 17 and tube 19 when the unit is in action, see Figs. 1 and 2. The main casing 1 is also provided with a threaded hole 33 located in axial alignment with the inlet opening 8 and supply pipe 30 and within which the shut-off valve 15 is manually adjustable so as to either cut off the fresh liquid supply completely, or to throttle this supply and reduce the pressure thereof; and the valve 15 may be thus adjusted with the aid of an ordinary screw driver, and may be provided with a packing or sealing gland 34 in order to prevent undesirable leakage when the valve 15 is open and the valve 20 is closed, see Figs. 4 and 5.

The partition 10 is preferably formed integral with the casing 1, and the valve seat 13 and bore 21 should be machined to insure accurate co-operation of the automatic valve 20 with its seat 13; and the renewable valve disk 22 may be formed of hard rubber, fibre or other suitable material, and is snugly fitted within a slightly tapered inner end recess in the cylindrical valve

body. If so desired, this seating disk 22 may be additionally attached to the valve 20 with the aid of a central screw in a well known manner, but such additional fastening is optional. The plunger valve 20 should snugly but slidably coat with the bore 21 so as to avoid excessive leakage, but since the bore 21 is disposed at the low pressure side of the valve 20 and the spout 16 is always in open communication with the flush tank, very little leakage will ever occur past the valve body. The delivery nozzle 17 is detachably secured as by screw threads, to the swinging end of the spout 16, and the silencer screens 18 are spaced apart by means of washers 36 and are normally held in place by the nozzle 17 but are readily accessible for inspection upon release of this nozzle, see Fig. 5. The screw 27 affords simple means for varying the opening movement of the valve 20, and this screw is preferably provided with a lock nut 34.

The overflow pipe refill tube 19 which projects laterally away from the swing spout 16 may either be fixedly or adjustably secured to this spout with the aid of a clamping nut 35 so as to permit accurate alignment of the jet 32 with the upright overflow pipe 37 disposed within the flush tank and with the lower end of which the main ball discharge valve or plug 38 is associated, see Fig. 3. The lower extremities of the fresh liquid supply pipe 30 and of the overflow pipe 37 are normally secured and sealed relative to the flush tank bottom 40 to a well known manner; and in cases where the supply pipe 30 is furnished as part of the improved ball cock unit, the height of this pipe 30 should be such that the lower extremity of the liquid delivery nozzle 17 will finally be disposed well above the upper extremity of the overflow pipe 37 in order to positively prevent back-siphoning of liquid from the flush tank into other parts of the same plumbing system even when the valves 15, 20 are wide open and the liquid supply pressure is exceptionally high. The lower extremity of the fresh liquid supply pipe 30 should therefore be vertically adjustably attached to the tank bottom 40 as by nuts 41 in order to permit proper disposition of the ball cock unit at a height sufficient to comply with anti-siphon codes, in all cases, and the discharge end of the refill tube 19 should always be located above the outlet end of the nozzle 17.

The improved means associated with the float lever 25 and with the casing 1 of the unit, for retarding the closing motion of the float 28 so as to augment the buoyancy thereof sufficiently to insure rapid and positive closing of the valve 20, comprises an auxiliary lever 43 having one end pivotally attached to the float lever 25 near the pivot 26, by means of a pin 44, while its opposite swinging end carries a weight 45 and its medial portion is provided with a tapered abutment 46; and a rod 47 having a looped end 48 loosely embracing the main lever 25 and cooperable with the abutment 46 while its opposite end is bent laterally to form a pivot 49 coacting with a fixed rod 50 secured to and depending from the main casing 1. The abutment 46 is preferably adjustable toward and away from the axis of swing of the weighted lever 43, and while such adjustment may be accomplished in various ways, the simple adjusting means shown consists of a series of holes 51 formed in the pivoted end of the lever 43 and with any of which the pivot pin 44 may be caused to cooperate. The main float lever 25 is also preferably provided

with a stop lug 52 which is cooperable with the bottom of the main casing 1 to limit the downward swinging motion of the float lever 25 whenever flushing takes place, and the abutment 46 has a more abrupt taper on one side than on the other, see Figs. 1, 2 and 3.

With this improved mechanism, when a flushing of the toilet is being or has been effected by manual lifting of the plug 38 in the usual manner, fresh liquid will initially be admitted to the tank from the nozzle 17 and into the overflow pipe 37 from the refill tube 19 in the form of full jets 31, 32 as illustrated in Fig. 1, whenever the plug 38 is elevated and for sometime after it has again been seated. As the liquid 53 rises within the tank, it engages and lifts the float 28 thereby swinging the levers 25, 43 upwardly about the pivot 26, and thus causing the screw 27 to partially close the automatic valve 20. The ascending float lever 25 eventually causes the more abrupt taper of the abutment 46 to engage the fixed rod loop 48, thereby retarding the upward motion of the float 28 and lifting the auxiliary weighted lever 43 as illustrated in Fig. 2. The closing motion of the valve 20 will then be momentarily arrested and the sizes of the jets 31, 32 emanating from the nozzle 17 and refill tube 19 will be reduced as shown; and when the buoyancy of the retarded float 28 has been sufficiently augmented, the abutment 46 will snap past the loop 48 and the lever 25 will be swung upwardly very rapidly to thereby cause the screw 27 to quickly and positively close the valve 20 and to thus entirely cut off the flow and eliminate the jets 31, 32. Subsequent flushing of the toilet will cause the less abrupt taper of the abutment 46 to ride over the stationary rod loop 48 and the weight 45 will thereafter cause the lever 43 to drop into parallelism with the float lever 25, and the downward swinging motion of the latter and of the float 28 will be arrested by engagement of the lug 52 with the fixed valve casing 7.

This functioning of the improved mechanism is entirely automatic and by properly adjusting the position of the control valve 15 with the aid of a screw driver to conform with the available liquid supply pressure, and by also manually adjusting the screw 27 to vary the extent of opening and the time of closing of the flow regulating valve 20, any desired rate and degree of filling of the tank may be effected. The exact moment of final complete and positive closing of the regulating valve 20 so as to eliminate subsequent leakage and dripping, may be obtained by adjusting the abutment 46 toward and away from the pivotal axis of the lever 43 with the aid of the pin 44 and holes 51, and the screens 18 cooperate with the diminishing main jet 31 to effectively silence the admitted liquid while the location of the nozzle 17 and refill tube 19 positively prevents back siphoning of liquid through the ball cock. When installing the improved unit, the casing 1 may be readily disposed at the proper height relative to the overflow pipe 37 so as to properly position the spout 16 as to elevation, and this spout may be subsequently angularly adjusted so as to cause the jet 31 to be delivered at the proper locality within the flush tank, while the outlet end of the tube 19 may also be properly located with respect to the overflow pipe 37 with the aid of the adjusting nut 35 without necessarily bending this refill tube. The main casing 1 may also be readily angularly adjusted relative to its supporting pipe 30 so as to permit the float 28 to swing freely;

and when proper adjustment of the valve actuating screw 27 has been accomplished, this screw may be locked in adjusted position with the aid of the nut 34. All of these various adjustments may be conveniently and quickly effected and when properly made, will insure silent, safe and most efficient operation of the unit for an indefinite period of time.

From the foregoing detailed description of the construction and operation of my improved ball cock assemblage, it will be apparent that I have in fact provided a unit which besides being simple, compact and durable in construction, is also highly efficient in operation and flexible in its adaptations so as to meet various operating conditions. The improved assembly besides filling the flush tank quickly and quietly regardless of the available supply pressure, meets various plumbing code requirements as to safety. It is unnecessary with the improved mechanism to bend or otherwise distort parts in order to obtain proper installation, and the degree of filling of the flush tank may be accurately predetermined with the aid of the micrometer adjustment afforded by the valve actuating screw 27 which is at all times readily accessible for manipulation. The shut-off valve 15 associated directly with the unit may be adjusted at any time so as to control the liquid pressure within the casing 7, and when this valve 15 is closed the supply of liquid is cut off and the piston valve 20 may then be quickly removed from the casing bore 21 by merely removing the pivot 26 and withdrawing the float lever 25. The valve disk 22 may then be quickly replaced, and the life of these disks 22 is augmented to a maximum by the positive and quick seating afforded by the float retarding abutment 46.

As previously indicated, the float retarding mechanism is an extremely important feature of this invention, as it causes the valve 20 to finally close with great rapidity after the flow has been initially throttled, and this rapid closing of the valve 22 eliminates subsequent noisy leakage and dripping while also insuring accurate and equal subsequent tank fillings. It has been found that the height of fill may be accurately predetermined with the aid of the adjustable abutment 46 so as to insure efficient flushing with least waste of flushing liquid 53, and it has also been found that the float buoyancy augmenting effect may be secured by effecting adjustment of the abutment 46 in various ways. The simplicity of the various parts of the improved mechanism shown, however, permit manufacture and sale of these flush valve units at moderate cost, which have proven highly efficient and satisfactory in every respect, in actual use.

It should be understood that it is not desired to limit this invention to the exact details of construction and operation of the typical ball cock unit herein shown and described, for various modifications within the scope of the appended claims may occur to persons skilled in the art.

I claim:

1. A toilet flush valve assemblage comprising, a fixed casing having therein a valve for controlling the delivery of liquid to the flush tank, a float adapted to ride upon the rising liquid in the tank to close said valve and being swingably connected to said casing by a single rigid lever, an auxiliary lever pivotally suspended from said float lever to swing downwardly toward the latter and having an abutment thereon constantly biased downwardly toward but movable upwardly

away from the float lever, and an element having one end pivotally attached to said casing and an opposite end slidable along said float lever beneath said auxiliary lever and cooperable with said abutment to momentarily arrest the valve closing motion of the float lever and to subsequently effect final closing of the valve with a snap action by moving the abutment upwardly away from said float lever.

2. A toilet flush valve assemblage comprising, a fixed casing having therein a valve for controlling the delivery of liquid to the flush tank, a float adapted to ride upon the rising liquid in the tank to close said valve and being swingably connected to said casing by a rigid float lever, an auxiliary lever having one end pivotally attached to said float lever while its opposite swinging end is weighted and its medial portion is provided with an abutment which is biased to swing by gravity toward said float lever, and an element having one end pivotally attached to said casing and its opposite end confined between and slidable along said levers and cooperable with said abutment to momentarily arrest the upward swinging motion of the float lever and to subsequently lift the auxiliary lever and the abutment away from said opposite element end to effect final closing of said valve with a snap action.

3. A toilet flush valve assemblage comprising, a fixed casing having therein a valve for controlling the delivery of liquid to the flush tank, a float adapted to ride upon the rising liquid in the tank to close said valve and being swingably connected to said casing by a rigid float lever, an auxiliary lever carried by and swingable upwardly simultaneously with said float lever and having one end pivotally attached to the float lever while its opposite end is weighted and its medial portion is provided with a tapered abutment biased to swing by gravity toward the float lever, and an element having one end pivotally attached to said casing and its opposite end provided with a loop confined between and movable along said levers and engageable with the taper of said abutment to momentarily arrest the valve closing motion of the float lever and to

thereafter suddenly lift the abutment over the loop to effect final closing of the valve with a snap action.

4. A toilet flush valve assemblage comprising, a fixed casing having therein a valve for controlling the delivery of liquid to the flush tank, a float adapted to ride upon the rising liquid in the tank to close said valve and being swingably connected to said casing by a rigid float lever, an auxiliary lever carried by and swingable upwardly simultaneously with said float lever and having one end pivotally attached to the float lever while its opposite end is weighted and its medial portion is provided with a tapered abutment biased to swing by gravity toward the float lever, an element having one end pivotally attached to said casing and its opposite end provided with a loop confined between and movable along said levers and engageable with the taper of said abutment to momentarily arrest the valve closing motion of the float lever and to thereafter suddenly lift the abutment over the loop to effect final closing of the valve with a snap action, and means for effecting adjustment of said levers to vary the position of said abutment relative to said float lever.
